(57) **CLAIM**

The ornamental design for a waste bag dispenser, as shown and described.

DESCRIPTION

FIG. 1 is a top perspective view of a first embodiment of a waste bag dispenser;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a top perspective view of an alternate embodiment of the waste bag dispenser shown in FIG. 1;

FIG. 9 is a front view of the refuse receptacle holder shown in FIG. 8;

FIG. 10 is a rear view of the refuse receptacle holder shown in FIG. 8;

FIG. 11 is a right side view of the refuse receptacle holder shown in FIG. 8;

FIG. 12 is a left side view of the refuse receptacle holder shown in FIG. 8;

FIG. 13 is a top view of the refuse receptacle holder shown in FIG. 8; and,

FIG. 14 is a bottom view of the refuse receptacle holder shown in FIG. 8.

The evenly dashed broken lines in all figures depict portions of the article that form no part of the claimed design. The long dash/short dash broken lines shown in FIGS. 1, 2, 4-9, and 11-14 depict environmental subject matter, specifically a waste bag, and forms no part of the claimed design.

1 Claim, 10 Drawing Sheets
